UNITED STATES PATENT OFFICE.

JUVENTCIO MALDONADO, OF NEW YORK, N. Y.

AUTOMATIC STATION-SIGNAL DEVICE.

Application filed May 11, 1927. Serial No. 190,612.

This invention relates generally to automatic station signals, and has more particular reference to a novel type of adjustable interior means therefor.

5 The invention has for an object the provision of an automatic station signal which will be efficient in action, and which, can be manufactured and sold at a reasonable cost.

For further comprehension of the invention, and of the objects and advantages thereof, reference will be had to the following description and accompanying drawing, and to the appended claims in which the various novel features of the invention are 15 more particularly set forth.

Referring to the drawing forming a material part of this disclosure:

Fig. 1 is a perspective view of a device constructed according to this invention.

20 Fig. 2 is a front view thereof seen from within the casing.

Fig. 3 is a sectional view taken on the line 3—3 of Fig. 2.

25 Fig. 4 is a sectional view taken on the line 4—4 of Fig. 2.

Fig. 5 is a sectional view taken on the line 5—5 of Fig. 2.

Fig. 6 is a schematic wiring diagram of the device.

30 Fig. 7 is an enlarged fragmentary view of a portion of Fig. 4.

The reference numeral 10 indicates generally a casing having a top cover 11, and a window 12 on one side, and another window 13 in the other side of the casing. A strip of material 14 is formed along its edges with apertures 15, and has printed on its outer surface two consecutive lists of stations in consecutive order, indicated roughly 35 by the names of stations 16 and so spaced that the same station names appear simultaneously at the windows 12 and 13. Several rollers 17 suitably mounted within the casing guides the strip of material 14.

40 Suitably mounted within the casing is an electric motor 18 having on its shaft a pinion 19, which meshes with a large gear 20 having a small gear 21 coaxially mounted. This small gear 21 meshes with a broad gear 22 meshing with a narrow gear 23 slidably mounted on a shaft 24, and having a grooved collar 25 engaged by a fork 26 which is pivoted at 27 and connected to a 45 lever 28 projecting through a slot 29 in casing 10. Mounted on opposite sides of the gear 23 are other gears 30, 31 in different

planes, as shown in Fig. 5, so that gear 23 meshes with either gear 30 or 31, depending on the position of lever 28. The gear 30 connects with a roller 32 capable of driving the strip 14, while gear 31 connects with another roller 33 also capable of driving the strip 14. When gears 23, 31 mesh the strip 14 is driven in one direction, while when gears 23, 30 mesh the strip is driven 60 in the other direction, so as to correctly display the station irrespective of the direction in which a train may run having the invention device.

65 Suitably mounted in the casing 10 is a roller 34 having teeth 35 engaging in the apertures 15 of strip 14, and this idler is formed with a pair of diametrically opposite slots 36 engageable by a tongue 37 slidably mounted and controlled by a solenoid 70 75 38 so that when current flows in the solenoid, the member 37 is disengaged from the slot 36 permitting the strip 14 to advance, and the current is automatically cut off, hereafter explained, to permit the member 37 to engage the next slot 36, thus allowing $\frac{1}{2}$ rotation each time, of roller 34, and allowing a certain amount of advancement of the strip 14. The rollers 32, 33 slip against the strip 14 when the strip is locked by the 80 idler 34.

85 Projecting from the roller 34 is a pin 39 engaged in a slot 40 formed by the side of make and break lever 41 and a rod 42 slidable in grooves 43 in projections 44 from 90 the lever 41. Cam arms 45 act against the rod 42, and are connected with lock pins 46 engaged by pawls 47 urged into engagement by springs 48, while other springs 49 normally urge the rod 42 against the cam 95 arms 45 by acting between the rod 42 and the projections 44. It should be understood that the movement of the make and break lever 41 may be predetermined by adjusting the width of the slot between the 100 edge thereof and the edge of the adjustable bar 42. When the slot is increased in width by setting of the pawl 47 so as to position cam 45 at an angle to the bar 42 the movement of the lever 41 for each half revolution of the roller 34 is decreased.

105 The make and break lever 41 is pivoted at 50 and has its other arm 51 formed with a contact 52 engageable with a stationary contact 53 when 37 engages one of the slots 110 36, or with a contact 54 when 37 engages the other of the slots 36.

One lead 55 of motor 18 connects to batteries 56 thereafter to the handle contact of the two way switch 57. Contact 58 of the switch connects to contact 54, while contact 59 connects to contact 53. The contact 52 of the lever 41 is connected with the pivot point 50, and lead 60 connects 50 to solenoid 38, a single throw switch 61, thereafter to the motor 18.

10 In operating the device, lever 28 is moved to have 23 engage 30 or 31 as desired. The motorman engages handle 62 of switch 57 against the contact 59. A current then flows from the battery 56 to handle contact 15 of the switch 57, to 59, 53, 52, 50, 60, through solenoid 38, switch 61, which must be closed, and the motor 18, back to battery 56. The energized solenoid moves 37 free from slot 36. Motor 18, through the chain of gears, 20 drives the strip 14, which also moves the roller 34, and pin 39 moves make and break 41. When the pin 39 reaches the diametrically opposite side of its original position, contacts 52 and 53 break, while 52 and 54 make. Immediately solenoid 38 allows 37 to 25 engage a slot 36 holding the strip 14 in its new position, while the motor 18 comes to a stop. At the next station, the motorman throws 62 onto 58. A complete circuit then 30 exists between the battery 56, the switch 57, contact 58, contacts 54, 52, 50, 60, 38, 61, 18, and back to 56. A repetition of that just 35 before explained occurs, and this may be continued for each station.

The direction of travel of ribbon 14 may 40 be automatically reversed by providing lever 28 with an arm 28', and providing the ribbon 14 with a trip bar 14' adapted to move the arm 28' at a certain position of the ribbon so as to shift the gears as may be manually shifted by operating lever 28.

While I have illustrated and described my invention with some degree of particularity, I realize that in practice various

alterations therein may be made. I therefore 45 reserve the right and privilege of changing the form of the details of construction or otherwise altering the arrangement of the correlated parts without departing from the spirit or the scope of the appended claims. 50

Having thus described my invention, what I claim as new and desire to secure by United States Letters Patent is—

1. In a device of the class described, the combination with a roller provided with 55 means for gripping a printed strip, and having a projecting pin, of a make and break pivoted lever, projections from said lever, a rod slidable in grooves in the projections the rod and the lever forming a slot for 60 engaging the said projecting pin, cam arms actable against the rod, pinions secured to the cam arms, means for normally urging the rod against the cam arms, and means for locking the pinions in adjusted positions. 65

2. An automatic station signal, comprising a casing, rollers mounted therein, a strip mounted on said rollers, a motor driven means for moving the strip towards the front or rear of the casing, a control roller 70 gripping the strip, a solenoid operable tongue normally engaging the control roller for locking it against rotation, a pin extending from the said control roller, a make and break operable by the pin upon rotation 75 of the control roller, a power circuit including the said motor, the said solenoid, the said make and break, and a two pole switch for energizing the motor and solenoid upon engaging the switch on one pole, to free the 80 control roller and to advance the strip until the circuit is broken by the make and break, and upon engaging the switch on the other pole, to repeat the operation.

In testimony whereof I have affixed my 85 signature.

JUVENCIO MALDONADO.
